Warren E. Losh, 4086 Wayside Lane, Carmichael, Calif.

Filed Aug. 3, 1962, Ser. No. 71,173

Term of patent 14 years

(Cl. D93—4)

FIGURE 1 is a front perspective view of a combined screwdriver and wire stripper showing my new design;
FIGURE 2 is a top plan view;
FIGURE 3 is a front elevational view;
FIGURE 4 is a bottom plan view; and
FIGURE 5 is a side elevational view.
The undisclosed rear is substantially the same in appearance as the front.

I claim:
The ornamental design for a combined screwdriver and wire stripper, as shown and described.
